UNITED STATES PATENT OFFICE.

HANS SPRUTH, OF BERLIN-LANKWITZ, GERMANY.

LOCK.

Application filed March 10, 1923, Serial No. 624,232, and in Germany March 13, 1922.

My invention relates to locks and more especially to locks of the kind in which the locking or unlocking is effected by means of a key actuating the lock by merely being inserted therein, and where annular tumblers are provided in a stationary or rotatory cylinder, such tumblers being rotated by a curved groove provided in the key and acting on a bolt or equivalent member. In locks of this kind hitherto known the tumblers must be provided with braking springs or with abutment lugs and retracting springs and their arrangement is such that the key can be introduced only if all tumblers assume a certain definite position relatively to each other.

In the improved lock according to the present invention the annular tumblers are freely rotatable in their casing and co-operate with a key having at the free end of its shaft a more or less pointed projection formed of two converging and preferably helical faces. This projection co-operates with interior lugs of the rotatory tumblers which latter are positively turned by the key while it is introduced into the lock to such an extent that notches provided in the tumblers form a continuous straight groove permitting of the introduction of the bolt or latch or the like. The rotatability of the annular tumblers, as just mentioned, may, however, be restricted, if desired, in such a manner that the extent of motion of each tumbler relatively to its neighbouring tumbler or tumblers amounts only to a small angle whereby it is rendered possible to make the pointed end of the key very short and practically obtuse without interfering with its insertion.

As the tumblers used in my improved lock permit of being arranged in large numbers side by side, and as there is no spring whatever co-operating with them, the security and the velocity of locking and unlocking is considerably increased. The free rotatability of the tumblers renders it practically impossible to turn the latter singly into the opening position by means of a false key or a lock-picker. Besides, the guide groove or slot provided in the key may have various configurations so that an unlimited number of locks of the same construction may have keys with guide grooves or slots of different shape. The invention is applicable to locks

of any kind, such as door-locks, safe locks, pad-locks, and so on.

In the drawings affixed to this specification and forming part thereof several locks embodying my invention are illustrated by way of example. In the drawings

Figure 1 is a longitudinal section of a padlock, the U-shaped bolt or yoke being unlocked and ready for withdrawal.

Figure 2 is a transverse section on the line *a—b* in Figure 1.

Figure 3 is a plan and

Figure 5 is a plan of a finished tumbler.

Figure 6 is an illustration similar to Figure 1, showing the U-shaped bolt or the yoke in locked position.

Figure 7 is a view of the key co-operating with the lock illustrated in Figures 1 and 6.

Figure 8 shows the same key turned 90° and partly in axial section.

Figure 9 is an axial section of a modified tumbler casing and its tumblers.

Figure 10 is a transverse section on the line *c—d* in Figure 9.

Figure 11 is an illustration of the key designed to co-operate with a lock having tumblers of the kind shown in Figures 9 and 10.

Figure 12 is a plan of a tumbler as shown in Figures 9 and 10, drawn to a larger scale.

Figure 13 is a side view of two neighbouring tumblers of the same kind.

Figure 14 is an axial section through one such tumbler.

Figure 15 is a frontal view of the working end of the key shown in Figure 11, the scale being the same as of Figures 12-14.

Figure 16 is an illustration similar to Figure 12, showing a pressed sheet-metal tumbler.

Figure 17 is a transverse section on the line *e—f* in Figure 16.

Figure 18 is a transverse section on the line *g—h* in Figure 16.

Figure 19 is an illustration similar to Figure 15 and relating to the key used in connection with tumblers of the kind shown in Figures 16-18.

Figure 20 is a side-view of a lock provided with tumblers and a tumbler casing constructed according to this invention, some parts being shown in vertical section.

Figure 21 is a section on the line A—B in Figure 20, the tumbler sleeve being shown in side view as viewed from the left in Figure 20.

5 Figure 22 is a separate illustration of the locking member or bolt pertaining to the lock shown in Figures 20 and 21.

Figure 23 is a side view of a modified tumbler sleeve.

10 Figure 24 is a transverse section on the line C—D in Figure 23.

Figure 25 is a transverse section on the line E—F in Figure 23.

15 Figure 26 is a side view of a tumbler sleeve having a divided locking member.

Figure 27 is an illustration similar to Figure 20 showing another modification.

Figure 28 is a section on the line G—H in Figure 27.

20 Figure 29 is a horizontal section on the line I—K in Figure 27.

Figure 30 is a side view, as well as a transverse section of the locking bolt pertaining to the lock shown in Figures 27—29, 25 and

Figures 31, 32 and 33 show details, also fully described hereinafter.

In Figures 1—8, the invention is shown as applied to a padlock. The lock casing consists of two plates 1 and 2 connected with each other by a sleeve 4 provided with a longitudinal slot 3. Within the sleeve 4 is located a plurality of annular tumblers 5 having each an internal lug 6, as well as an external notch 7 (Figure 5). The plate 1 is the top plate of the padlock; it is provided with two bores 8 and 9 permitting the insertion into the lock casing of the limbs of a U-shaped locking member or shackle 10. The position of the bore 8 is such that it coincides at least partly with the circumference of the tumbler disks 5 and forms a continuation of the groove or channel formed by the notches 7 if the position of all tumblers 5 is that shown in Figures 1 and 2. The limbs of the shackle 10 can be inserted only if the tumblers are in that position.

Each limb is provided with a recess 11, the length of which corresponds to the thickness of the disk 1 and the depth of which corresponds to the depth of the notches 7 of the tumblers 5. The shackle limbs may, thus, be shifted laterally with respect to the disk 1, that is to say, they may assume the position illustrated in Figure 6, into which the limbs are moved by any one of the tumblers, as well as by all together, as the case may be. If the tumblers are rotated in unison, or if any one of them is rotated separately so as to make the adjacent part of the limb leave the notch of the respective tumbler or tumblers, that motion of the latter entails a motion of the shackle limbs from the position Figure 1 to the position Figure 6, the top disk 1 of the lock casing entering, at

the bores 8 and 9, the recesses 11 of the shackle limbs whereby the shackle is checked and the lock is, therefore, locked up. The recesses 11 and, in connection therewith, collars 12 provided between the shackle proper and the limbs proper of the locking member 10 prevent this latter from assuming an oblique position with respect to the tumblers. The sleeve 4 may be provided, if desired, with a lug 13, Figures 1 and 6, engaging when the lock is locked up a recess 14 provided in the adjacent limb of the shackle. Of course, there may be more than one such lug and recess.

Rotation of the tumblers 5 is effected by a suitably constructed key 15, of which Figures 7 and 8 show one of the many configurations possible. The shank of this key is hollow and a multi-curved slot 16 is milled thereinto. The shape of this slot may be chosen as desired, and its portions may be curved in one or the other direction, preferably always beyond 45°. The free end of the shank is cut off obliquely and forms two curved guide surfaces 18, as well as an edge 19 or a point 17. The key may be introduced into the lock in any desired position. Whatever the position may be, one or the other of the guide surfaces 18 contacts with the interior lug 6 of the first tumbler and thereafter with the consecutive lugs of the other tumblers. The position of the lugs 6 of the tumblers relatively to the position of their notches 7 corresponds to the position of the various portions of the key slot 16 relatively to the point 17, in consequence whereof the tumblers are so turned by the inserted key that their notches 7 are placed side by side so as to form a channel adapted to receive one of the limbs of the yoke 10. The tumblers have arrived in their final position when the key grip 19 contacts with the lock disk 2.

An important feature as regards the right position of the notches 7 relatively to the pins 6, viz corresponding to the configuration of the key slot 16, lies in the fact that the notches are milled into the tumblers only after the pins 6 have been inserted, the tumblers having then the appearance shown in Figures 3 and 4. These unfinished tumblers are now shoved on the key, their pins entering into the slot 16 whereby the right position of the tumblers relatively to each other is determined. Now the notches are milled into the tumblers on the key, in that a continuous channel is milled thereinto parallel to the axis of the key. The thus finished tumblers are shoved into the sleeve 4, without changing their order. Irrespective of the position of the tumblers, they are adjusted so as to make the notches 7 form a channel merely by the insertion of the key 15 which thereafter is so turned that the combined notches, or the channel re-

spectively co-incides with the bore 8. A mark may be provided at the lock casing or at the key or at both parts which facilitates finding that position.

- 5 With the above-described construction of the tumblers, all of them are positively rotated and the shackle limbs are locked by either a rotatory movement of the key or a longitudinal movement thereof. This locking takes place at even a slight part rotation of the key, or withdrawing it but partly, the shackle limbs being in either case shifted laterally. The security obtained in locking, or preventing unauthorized unlocking 15 of the lock is very great. It is also obvious that a practically unlimited number of locks of the same type may be manufactured to which pertain keys distinguished from each other merely by the different configurations of their slots 16. Making a false key which is an exact copy of the original is practically out of the question as is also adjusting the tumblers by a pick lock or the like. The security the lock offers 20 is, thus, extraordinarily great and unparalleled as regards locks of the kind in question, the more so since the tumblers may consist of thin sheet-metal and their number may be very great.
- 30 With the lock illustrated in Figures 1-8 all tumblers are freely rotatable in the casting or sleeve 4. The rotatableness may, however, be restricted with respect to the neighbouring tumbler or tumblers, as is the case in the modification shown in Figures 9-15. The tumblers 5 are also in this case rotatable in their common sleeve 21 which is provided with a longitudinal slot 3, they are prevented from leaving the sleeve 35 by means of a cap-nut 22. Each tumbler is coupled with its neighbouring one or ones by a member permitting only of a restricted rotatory movement of the respective tumblers relatively to each other. In the example 40 shown said members consist of balls 24 located in circularly curved slots 23, of which there are always two co-operating with one ball or its equivalent.
- 50 Another difference, as regards the tumblers, consists in the substitution of central apertures of non-circular shape, such as 20' in Figure 10. There are in the modification in question semi-circular apertures 20' as shown in Figs. 9 and 10 the chord of 55 which is engaged by the key. This latter is not hollow, but its sectional shape corresponds to that of the apertures 20', and it is distorted in the manner shown in Figure 11, these distortions being an equivalent to 60 the multi-curved slot of the key of the first-described lock. The sectional shape of the key 15, Figure 11, is the same along the whole length of the distortions, always corresponding to the aperture 20'. At the free 65 end of the key shaft is an oblique guide sur-

face 18' by which the tumblers are so turned by means of the inserted key that their notches 7 are made to lie side by side so as to form a channel for the reception of a yoke limb, as in the first case.

70 The limited rotatableness of the tumblers permits of making the end 18' materially shorter, also rather obtuse, as while said end enters into an aperture 20' and rotates the respective tumbler this latter takes along 75 with it the neighbouring tumbler with which it is coupled by the respective ball 24, the next tumbler being thus positively turned into such a position that the end 18' of the key gets into the range of action of that 80 end. If this range extends over a certain definite angle, say two times 45°, the grooves 23 need extend only over 45°.

85 The restricted rotatableness of neighbouring tumblers may be brought about, instead of by balls or the like, also by stationary projections engaging slots of the neighbouring tumbler or tumblers. The projections may be formed by pressed-out parts of the tumblers, as shown, by way of example, in 90 Figures 16-18 in which the tumbler consists of sheet-metal and is provided on one side with conical projections 25' formed by pressed-out parts of the tumbler, and on the other side with a short radial rib 26 which extends above the respective plane of the tumbler. If the tumblers are placed side by side in such a manner that the ribs of one tumbler engage the conical projections of the other side, the rotatableness of 95 the thus coupled tumblers is correspondingly limited. The apertures receiving the key are oblong, as shown at 20" in Figures 16 and 18, and the free end of the key 15, Figure 19, is correspondingly shaped and 100 provided with oblique guide surfaces 18".

105 The novel lock mechanism may be used in connection with locks of any kind. If it is intended for a door-lock, the sleeve 21, Figures 9 and 10, is arranged rotatably in the lock casing and rotated by means of the key, whereby it is changed into a tumbler box. It is rotated by means of a driver formed by a projection 27, Figure 11, of the key, the projection engaging a recess 28, Figure 9, of said box.

110 In order to be able to use the key at both sides of the lock, the multi-curved slot 16, Figures 7 and 8, or the distorted surface 18', Figure 11, may be arranged 115 symmetrically with respect to the middle line $\alpha-\alpha$ (Figure 11) of the key, but the key halves extending from the line $\alpha-\alpha$ to one and the other end of the shank may be differently shaped and also their pitches 120 may be different.

125 Figures 20 and 21 show the parts as used in a door lock. The lock casing is provided with an internally threaded spacing ring 32, into which is screwed a casing 33 that en-

closes the tumbler box 34. This casing is provided with a longitudinal recess 35 receiving the locking member 36, and within the box 34 is a plurality of tumblers 5 which may be rotated and adjusted by means of a key in the manner described with respect to the preceding figures. According to the position of the notches 7 of the tumblers these latter permit of the locking member 36 moving back wholly into the longitudinal slot 3, or said member is pressed into the recess 35 of the stationary casing 33, whereby the tumbler box is prevented from further rotation.

15 The bolt 38 is located below the tumbler box and provided with tooth-like projections 40, 41 and 42. The locking member 36 may enter into the spaces existing between said projections and may then act 20 upon the bolt, which extends through a segment-shaped slot 39 of casing 35 into an annular groove 45 of the tumbler box 34. The slot 39 extends through the spacing ring 32 and the casing 33, and the bolt 38 holds the box 34 in its position.

25 The tumbler box is provided also with annular grooves 45' which all cross the longitudinal slot 3. This slot forms a guide for the locking member 36 which is provided 30 with tooth-like projections 36' extending into the free space formed by the annular grooves 45 and 45' whereby lateral removing of the locking member is rendered impossible. Such a locking member may be 35 manufactured in the most simple manner from a cylindrical piece having lateral parallel flat surfaces 36" forming guide-surfaces in the longitudinal slot 3 (Figures 22 and 23). The central projection of the 40 projections 36' acts as a tooth on the latch 38, and all these projections hold the locking member 36 in the right position. This member may have, of course, any other desired 45 sectional shape, as well as such other milled-off parts as are suited to the purpose.

50 In order to permit the locking member 36 to move, with the teeth that extend beyond the slot 3, from the locking position into the open position, that is to say, radially, the tumbler box is provided with a flat part 37 located at the inner end of the slot 3.

55 Figures 23-25 show a modification of the tumbler box. It differs from that just described only in the feature that the annular grooves 45' are dispensed with and are substituted by milled recesses 47 between which the teeth 36' extend beyond the longitudinal slot 3. Said recesses 47 are substituted for the flat parts 37 of the before-described construction. The modified form presents the advantage that also small tumbler boxes may be provided with annular tumblers.

60 65 With the two forms of constructions illustrated in Figures 21-25, the locking

member 36 extends along the whole breadth of the tumblers. In order to hinder burglars to get access to the lock by drilling a hole in the casing the locking member 36 may be divided into a plurality of members 70 46 as shown in Fig. 26 each of which is adapted to engage a longitudinal slot 3' in the periphery of the tumbler box 34, the slots and locking members being staggered.

75 In the modification illustrated in Figures 27 and 28 the casing for the locking device consists of two parts 33 and 33' which are screwed into the spacing ring 32 and abut against annular flanges or collars 34' located at, and bordering, the annular groove 45 of 80 the tumbler box.

85 The locking member used in connection with this lock consists of a somewhat oval shank 48, Figure 30, and of a central projection shaped like a key beard and consisting of a large main tooth 49 and of two lateral smaller teeth 50. The shank 48 and the beard or teeth 49, 50 are laterally flattened at 51, these surfaces being guide surfaces which contact with the lateral surfaces 90 of the longitudinal slot 3 provided in the middle flanges or collars 34'. The tooth or beard part 49 which projects beyond said flanges or collars forms the head of the locking member 48 which acts on the lock bolt. 95 The member 48 forms a kind of key having its beard in its central portion, the shank consisting of two parts extending each from said beard to the ends of the key, and co-operating with rotary tumblers of the kind 100 described.

105 Coupling the tumbler box with the casing parts 33 is obtained in this way that the vaulted parts of the teeth or beard parts 50 which lie between the flattened sides 51 enter into corresponding grooves 52 and 52' of the casing parts 33 and 33'. The flattened sides 51 of the locking member 48 render possible a good radial straight-line guidance 110 and makes, besides, the size of the teeth 49 and 50 independent of the height of the member 48 so that a uniform maximum strength may be obtained in all checking parts.

115 In order to be able to put the tumblers 3 easily and conveniently into the tumbler box 34 and to secure their right position therein without jamming, the box 34 is closed at one end by a cap-nut 22. In order to prevent this nut from being screwed out, the longitudinal slot of the box is extended through the rim of said nut, the end of the locking member 36, Figure 32, engaging the thereby cut-up rim and securing the cap-nut 120 against screwing out. The same safety means may be used if the tumbler box consists of two parts screwed one into the other.

125 130 The casing 33 used in connection with the tumbler casing of the lock illustrated in Figures 20 and 21 conditions a compara-

tively large diameter of the tumbler casing. In order to reduce this diameter and, thereby, the weight also, the corresponding casing of Figures 26 and 27 is made in two parts, 5 33 and 33', whereby at the same time the tumbler box 34 is accurately centered and guided by means of the middle flanges or collars 34'. There must, however, be provided and is provided, a safety means 10 against unauthorized unscrewing, said means consists of a yoke 53 shiftably supported in a slot 57 of the lock casing and provided with wedge-shaped projections 58' Figure 29, extending through lateral recesses 53, Figure 33, of the spacing ring 32 into corresponding notches 54, Figure 29, provided at the circumference of the casing parts 33 and 33'. The yoke 58 is pressed inwards by an adjusting screw 59 provided in 15 the lock casing 31 and ensures in this way permanently the spacing ring 32 and the casing parts 33 and 33' in their positions relatively to each other.

The bolt 38, Figure 27, is provided with 20 teeth at its upper rim, as well as at its lower one, whereby it is rendered possible to use the lock for right hand-closing and left hand-closing doors. The lower teeth co-operate with the latch sleeve 30 arranged in 25 the lock casing. There is at said sleeve a lug 30' against which presses the latch spring 29. A second lug 59 is so arranged with respect to the lower tooth 41' of the bolt that it enters below said tooth when the 30 bolt is in locking position. The right end position of the lug 59 is ensured by an abutment 56 provided in the lock casing. As the bolt is supported and guided by the front plate 55, as well as by the pin 60, also 35 the latch which is connected with the sleeve 30 is checked. If the key is so turned that the bolt is moved to the right (Figure 27) the tooth 41' is moved off the lug 59 which then is pressed against said tooth by the 40 spring 29 which moves the bolt further to the right. The other end position, at the right (Figure 27) is determined by the spring 61 which, however, can shift the bolt to the left only as far as allowed by an 45 abutment pin 62. Each of the two springs (29 and 61), therefore, shifts the bolt towards the other spring whereby accurate and quick closing is effected.

I wish it to be understood that I do not 50 desire to be limited to the exact details of construction shown and described, for obvious modifications will occur to a person skilled in the art.

I claim:

60 1. A lock comprising, in combination with a locking member, a sleeve; a plurality of tumbler discs closely nested in said sleeve for independent rotation and held against either independent or unitary axial movement relative to the sleeve, each of said discs

having a peripheral recess to receive said locking member and controlling the movement of said member radially of the sleeve to its locking and unlocking positions, a key, coacting means on each of said discs and the 70 key to relatively rotate the discs when the key is moved axially in one direction with respect thereto and align the recesses of said discs to permit movement of said member to its unlocking position, and said discs coacting with the locking member when the key is moved axially in the opposite direction to project said member to its locking position, and additional means operating in the 75 latter position of the locking member to prevent movement thereof axially with respect to the tumbler discs and the sleeve.

2. A lock comprising a plurality of annular tumbler discs and means for supporting said discs in closely contacting relation 80 with each other for independent rotary movement while preventing the independent or unitary axial movement thereof, each of said discs being provided with a recess in its outer periphery adapted to receive a locking member, an operating key provided with a longitudinally extending sinusoidal surface and adapted for axial movement through the tumbler discs, each of said discs having a surface at its inner edge adapted 85 to be engaged by the sinusoidal surface of the key whereby said discs are successively rotated to align the peripheral recesses thereof with each other for the reception of the locking member, and said discs upon withdrawal of the key adapted to independently 90 coact with the locking member to project the same to locking position.

3. A lock comprising a sleeve, a plurality 95 of tumbler discs arranged within the sleeve 100 in close contacting relation with each other for independent rotary movement, each disc having means to cooperate with a locking member, a key having a longitudinally extending surface to coact with a surface on 105 each of said tumbler discs in the axial movement of the key to rotate said discs relative to each other, and the opposed contacting surfaces of adjacent discs having coacting 110 coupling means thereon restricting the independent rotation of said discs.

4. A lock comprising a sleeve, a plurality 115 of tumbler discs arranged within the sleeve in close contacting relation with each other for independent rotary movement, each disc having means to cooperate with a locking member, a key having a longitudinally extending surface to coact with a surface on 120 each of said tumbler discs in the axial movement of the key to rotate said discs relative to each other, and means for limiting the independent relative rotation of the adjacent tumbler discs.

5. A lock comprising a sleeve, a plurality 125 of rotatable annular tumbler discs arranged 130

in said sleeve in closely nested contacting relation and restrained against independent or unitary axial movement, said sleeve having a longitudinally extending slot in its wall and each of the tumbler discs having a peripheral recess to register with said slot, a locking member radially movable in said slot, said sleeve also having a transverse slot in its wall intersecting said longitudinal slot, 5 said transverse slot adapted to receive a member to be locked, each of said tumbler discs being provided on the inner side thereof with a key engaging surface, and a key adapted to be inserted axially through said 10 discs and having a longitudinally extending sinusoidal surface to cooperate with said key engaging surfaces of the tumbler discs and successively rotate said discs to register the peripheral recesses thereof with the slot in the sleeve wall and thereby permit of the inward radial movement of the locking member into said recesses and said tumbler discs upon withdrawal of the key independently coacting with said locking member to project the same outwardly from the recesses of said discs and into engagement with the part projecting into said transverse slot in the sleeve wall.

6. In a lock, a casing, a sleeve rotatably mounted in the casing, a plurality of relatively rotatable tumbler discs in said sleeve, a locking member mounted in said sleeve for movement radially thereof, each of the tumbler discs having means to cooperate 30 with the locking member and permit movement of said member in one direction to its released position, a key, said key and the tumbler discs having coacting means operative in the axial movement of the key in one direction to rotate the discs and position said means thereof in cooperative relation with the locking member, said casing having means to permit movement of said locking member to its locking position, said 35 tumbler discs being relatively rotated in the axial movement of the key in the opposite direction to retain said member in its locking position and prevent rotation of said sleeve.

7. In a lock, a casing, a sleeve rotatably mounted in the casing, a plurality of relatively rotatable tumbler discs in said sleeve, a locking member mounted in said sleeve for movement radially thereof, each of the tumbler discs having means to cooperate 40 with the locking member and permit movement of said member in one direction to its released position, a key, said key and the tumbler discs having coacting means operative in the axial movement of the key in one direction to rotate the discs and position said means thereof in cooperative relation with the locking member, said casing having means to permit movement of said locking member to its locking position, said 45 tumbler discs being relatively rotated in the axial movement of the key in the opposite direction to retain said member in its locking position and prevent rotation of said sleeve.

8. In a lock, a casing, a sleeve rotatably mounted in the casing, a plurality of relatively rotatable tumbler discs in said sleeve, a locking member mounted in said sleeve for movement radially thereof, each of the tumbler discs having means to cooperate 50 with the locking member and permit movement of said member in one direction to its released position, a key, said key and the tumbler discs having coacting means operative in the axial movement of the key in one direction to rotate the discs and position said means thereof in cooperative relation with the locking member, said casing having means to permit movement of said locking member to its locking position, said 55 tumbler discs being relatively rotated in the axial movement of the key in the opposite direction to retain said member in its locking position and prevent rotation of said sleeve.

of the locking member in said sleeve to its locking position and said member having means cooperating with the sleeve to prevent longitudinal movement of said member in said recess, said tumbler discs being relatively rotated in the axial movement of the key in the opposite direction to retain said member in its locking position and prevent rotation of said sleeve.

8. A lock comprising a sleeve a plurality of closely contacting annular tumbler discs arranged in said sleeve for independent rotary movement while restrained by the sleeve against either independent or unitary axial movement, each of said discs being provided with a recess in its outer periphery adapted to receive a locking member, an operating key provided with a longitudinally extending sinusoidal surface and adapted for axial movement through the tumbler discs, each of said discs at the inner edge thereof having an angular surface adapted to be engaged by the sinusoidal surface of the key whereby said discs are successively rotated to align the peripheral recesses thereof with each other for the reception of the locking member, said inner edge surfaces of the several discs in the different positions thereof, compositely determining the average shape of the opening through the series of discs, and said key having a terminal portion substantially conforming in shape to said average shaped opening through the discs.

9. A lock comprising a sleeve, a plurality of annular tumbler discs arranged in said sleeve in closely contacting relation with each other for independent rotation while restrained by the sleeve against independent or unitary axial movement, each of the discs being provided with a recess in its outer periphery adapted to receive a locking member, an operating key having a longitudinally extending sinusoidal surface, the curvature of said surface being reversely symmetrical on opposite sides of a point substantially midway between its ends, and each of said discs having a surface at its inner edge engageable by the sinusoidal surface of the key when the latter is inserted through the openings in the discs from either side of the lock whereby said discs are successively rotated to align the peripheral recesses thereof with each other for the reception of the locking member.

10. A lock comprising a sleeve, a plurality of annular tumbler discs arranged in closely contacting relation with each other in said sleeve for independent rotation while restrained by the sleeve against independent or unitary axial movement, each of said discs being provided at its outer periphery with means with which a locking member is adapted to coact and each disc at its in-

ner edge having a surface adapted to be engaged by a key to successively rotate the discs and position the locking member engaging means thereof with relation to each other, and a key axially movable through the annular tumbler discs and having a longitudinally extending sinusoidal surface to cooperate with said key engaging surfaces of the discs, said sinusoidal surface from one end to the other thereof extending ¹⁰ transversely around at least 180 degrees of the key shank.

In testimony whereof I affix my signature.
HANS SPRUTH.
